(57) **CLAIM**

The ornamental design for a screwless faceplate, as shown
and described.

DESCRIPTION

FIG. 1 is a perspective view of a screwless faceplate
showing our new design;

FIG. 2 is a front elevational view thereof;

FIG. 3 is a left side elevational view thereof, the right side
being a mirror image;

FIG. 4 is a bottom plan view thereof, the top being a mirror
image;

FIG. 5 is a perspective view of the second embodiment of
the design of FIG. 1, the only difference being the lettering
on the front below the opening;

FIG. 6 is a front elevational view thereof, the remaining
views being identical to those of the first embodiment;

FIG. 7 is a perspective view of the third embodiment of the
design of FIG. 1, the only difference being the graphic
indicia in the lower left corner of the front;

FIG. 8 is a front elevational view thereof, the remaining
views being identical to those of the first embodiment;

FIG. 9 is a perspective view of a fourth embodiment of the
design of FIG. 1, the only difference being adaptation for the
second opening;

FIG. 10 is a front elevational view thereof;

FIG. 11 is a bottom plan view thereof, the top being a mirror
image, the remaining views being identical to those of the
first embodiment;

FIG. 12 is a perspective view of the fifth embodiment of the design of FIG. 1, the only difference being adaptation for the second opening and lettering on the front below the left opening;

FIG. 13 is a front elevational view thereof, the remaining views being identical to those of the fourth embodiment;

FIG. 14 is a perspective view of the sixth embodiment of the design of FIG. 1, the only difference being adaptation for the second opening and the graphic indicia in the lower left corner of the front;

FIG. 15 is a front elevational view thereof, the remaining views being identical to those of the fourth embodiment;

FIG. 16 is a perspective view of the seventh embodiment of the design of FIG. 1, the only difference being adaptation for the second and third openings;

FIG. 17 is a front elevational view thereof;

FIG. 18 is a bottom plan view thereof, the top being a mirror image, the remaining views being identical to those of the first embodiment;

FIG. 19 is a perspective view of the eighth embodiment of the design of FIG. 1, the only difference being adaptation for the second and third openings and the lettering on the front below the left opening;

FIG. 20 is a front elevational view thereof, the remaining views being identical to those of the seventh embodiment;

FIG. 21 is a perspective view of the ninth embodiment of the design of FIG. 1, the only difference being adaptation for the second and third openings and the graphic indicia in the lower left corner of the front;

FIG. 22 is a front elevational view thereof, the remaining views being identical to those of the seventh embodiment;

FIG. 23 is a perspective view of the tenth embodiment of the design of FIG. 1, the only difference being adaptation for the second, third and fourth openings;

FIG. 24 is a front elevational view thereof;

FIG. 25 is a bottom plan view thereof, the top being a mirror image, the remaining views being identical to those of the first embodiment;

FIG. 26 is a perspective view of the eleventh embodiment of the design of FIG. 1, the only difference being adaptation for the second, third and fourth openings and the lettering on the front below the left opening;

FIG. 27 is a front elevational view thereof, the remaining views being identical to those of the tenth embodiment;

FIG. 28 is a perspective view of the twelfth embodiment of the design of FIG. 1, the only difference being adaptation for the second, third and fourth opening and the graphic indicia in the lower left corner of the front; and,

FIG. 29 is a front elevational view thereof, the remaining views being identical to those of the tenth embodiment.
